(57) **CLAIM**

The ornamental design for a shoe as shown and described.

DESCRIPTION

FIG. 1 is a front, right, and top perspective view of a shoe, showing my design;

FIG. 2 is a rear, left and bottom perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a rear elevation view thereof; and,

FIG. 8 is a front elevation view thereof.

A shoe for a right foot is a mirror image of the shoe for a left foot as shown in FIGS. 1 to 8 and does not form a part of the claimed design.

The broken lines shown in the drawings are included for the purpose of illustrating portions of the shoe that form no part of the claimed design.
